By *Knights Cook* Jno. 5.

UNITED STATES PATENT OFFICE.

WARD S. IRELAND, OF ST. LOUIS, MISSOURI, AND WALTER E. LIPPERT, OF CINCINNATI, OHIO, ASSIGNEES, BY DIRECT AND MESNE ASSIGNMENTS, TO NATIONAL SHORT HAND MACHINE COMPANY, OF ST. LOUIS, MISSOURI, A CORPORATION OF DELAWARE.

TYPE-WRITING MACHINE.

1,312,179.

Specification of Letters Patent. Patented Aug. 5, 1919

Application filed November 18, 1916. Serial No. 132,077.

To all whom it may concern:

Be it known that we, WARD S. IRELAND and WALTER E. LIPPERT, citizens of the United States of America, residents, respectively, of the city of St. Louis, State of Missouri, and of Cincinnati, in the county of Hamilton, State of Ohio, have invented certain new and useful Improvements in Type-Writing Machines, of which the following 10 is a full, clear, and exact description, reference being had to the accompanying drawings, forming a part of this specification.

Our invention relates to a typewriting machine having a series of key levers which 15 are so formed that it is necessary or desirable to guide and reinforce different portions of the key lever structure. An object of the present invention is to produce a strong and simple means for guiding, alining and reinforcing a series of key levers. More specifically stated, one of the objects is to produce a very simple and highly efficient means for guiding simple key levers, thereby simplifying the key controlled 25 elements of a typewriting machine. Another object is to produce a very substantial means for guiding angular key levers having arms which diverge from a pivotal support.

With the foregoing and other objects in 30 view the invention comprises the novel construction, combination and arrangement of parts hereinafter more specifically described and illustrated in the accompanying drawings wherein is shown the preferred embodiment of the invention, but it is to be understood that changes, variations and modifications can be resorted to which come 35 within the scope of the claims hereunto appended.

40 The invention is particularly adapted for use in stenographic writing machines having long angular key levers which, on account of their shape and length, require a most efficient guiding device for accurately 45 guiding them in their movements and at the same time retaining the different elements of the key lever structure in their proper relative positions.

Figure I is a longitudinal section of a machine embodying the features of our invention.

Fig. II is a transverse section taken approximately on the line II--II, Fig. I.

Fig. III is a perspective view of one of the key lever guides.

To illustrate the preferred form of the invention, we have shown certain parts of a stenographic writing machine, including a housing 1, a typeholder 2, type 3 supported by said typeholder, a rotatable core 4 supporting a roll of paper, paper guides 5, 6 and 7, the strip of paper being movable from the roll, along the paper guides and to the rear of the machine, as shown clearly in Fig. I. An inking ribbon 9 is arranged between the type 3 and the strip of paper.

The key controlled devices include a series of long angular levers A, each of which is provided with an upwardly extending arm 10 at its front end and a character key 11 at the upper end of said arm. By the term "key lever", it is to be understood that we mean a lever provided with a key or a lever under the control of a key. Each key lever A comprises an arm 12 extending rearwardly from the arm 10 and an arm 13 extending upwardly from the rear portion of said arm 12. The series of key levers is pivotally supported, preferably by means of a pivot member 14 located at the junctions of the lever arms 12 and 13. The upper end of each lever arm 13 is provided with a forwardly extending hammer element 15 which lies adjacent to the type 3. Springs 16 tend to retain the key levers in engagement with an abutment member 17 which constitutes a stop for limiting the movement of the key levers. When one of the keys is depressed the key lever associated therewith turns about the axis of pivot member 14 and the hammer element 15 moves toward the type thereby forcing the paper and inking ribbon toward the type, with the result of printing one of the type characters on the paper. The key levers may be operated independently of each other, or any desired number of key levers may be operated simultaneously.

The means for guiding the key levers preferably includes an upper guide B located near the upper ends of the lever arms 13 and provided with a series of comb-like teeth or guide bars 18 which lie between said lever arms. The elements 18 are preferably formed integral with a back member 19 and also integral with a front member 20 which

lies below the printing type. Arms 21 arranged at opposite sides of the key levers constitute supports for the upper guide member B. It will be noted that this guide member is adapted to accurately guide the upper portions of the lever arms 13 in their movements toward and away from the type, at the same time very materially reinforcing the key lever structure near the upper ends of lever arms 13.

10 C designates a key lever guide which is preferably an angular device in the form of an L-shaped pocket conforming approximately to the shape of the angular portions 15 of the key lever. This key lever guide is located at the junctions of the key lever arms 12 and 13, and it preferably supports the pivot member 14. The key lever guide C is so constructed that it guides and reinforces 20 the key lever structure at points in front of and at points above the pivot member 14, thereby strengthening the key lever structure at points which heretofore have not been amply reinforced. This key lever guide 25 preferably includes a bottom member 23, a series of comb-like teeth 24 extending upwardly from said bottom member at points between the lever arms 12, a back member 25 located in the rear of the lever arms 13, and 30 comb-like teeth 26 extending forwardly from said back member 25, said comb-like teeth 26 being located between the lever arms 13. The bottom member 23, back member 25, and the comb-like guiding teeth 24 and 26 35 are preferably integrally connected together so as to form a very substantial and extremely simple guiding device. The series of comb-like teeth 24 guide and reinforce the key levers at points immediately in front of pivot members 14, and the series of comb-like teeth 26 guide and reinforce the lower portions of the lever arms 13 at points immediately above said pivot member 14. The series of lever arms 13 are thus reinforced 40 near their lower ends to positively prevent them from bending or becoming in any way disarranged at this point. Arms 26, extending from the key lever guide C, are securely fastened to the frame or housing 45 of the machine.

The universal bar associated with the key levers includes a transverse abutment holder 27 arranged in front of the lever arms 13 and provided with a yieldable abutment 28 which engages all of said lever arms 13. The universal bar also includes a pair of arms 29 and 30 pivotally supported by the pivot member 14 and secured near their upper ends to the abutment holder 27. These arms are provided with extensions 31 which project forwardly from the pivot member 14, said extensions 31 and the lower portions of arms 29 and 30 being arranged within angular grooves 32 formed in the key lever guide C at points on opposite sides of the key levers.

33 designates a connecting member uniting the arms 29 and 30 of the universal bar, said connecting member being located at the rear of lever arms 13. 34 designates a restoring spring tending to retain the universal bar in the position shown in the drawings. The universal bar is adapted to move in response to movements of any one of the key levers, and its movement is limited by a yieldable stop member 35, shown in Fig. I.

70 The universal bar is adapted to operate a paper feeding device and various devices (not shown) which form no part of the present invention. The abutment holder 27 forming part of the universal bar and provided with the yieldable abutment 28 which engages all of the key levers, is preferably located between the upper and lower key lever guides B and C.

75 The printing elements herein shown are claimed in an application for patent filed by W. S. Ireland on Nov. 18, 1916, Serial No. 132,076. The universal bar is claimed in an application filed by W. S. Ireland and W. E. Lippert on Nov. 18, 1916, Serial No. 132,078.

80 We claim:

1. In a shorthand machine having angular key levers and a key lever guide in the form of an angular pocket for said angular key levers, said pocket having walls arranged at an angle to each other and provided with angular comb-like teeth which engage said angular key levers.

95 2. In a shorthand machine; a series of key levers each having two arms, a pivotal support for said key levers, and a key lever guide in the form of an angular pocket receiving the junctions of said arms, said angular pocket having a series of comb-like teeth in front of said pivotal support and a series of comb-like teeth immediately above said pivotal support.

100 3. In a shorthand machine, a series of key levers each having two arms, a pivotal support for said key levers, and key lever guides including a bottom member below said key levers, comb-like teeth extending upwardly from said bottom member, a rear member extending upwardly from said bottom member and comb-like teeth extending forwardly from said rear member.

110 4. In a shorthand machine, a series of key levers each having two arms, a pivotal support for said key levers, and key lever guides including a bottom member below said key levers, comb-like teeth extending upwardly from said bottom member, a rear member arranged at an angle to said bottom member, and comb-like teeth extending forwardly from said rear member, said bottom member, rear member, and comb-like teeth being integrally connected together.

115 5. In a shorthand machine, a series of key levers each having two arms, a pivot member near the junctions of said arms, and

an angular key lever guide at the junctions of said arms, said angular key lever guide comprising a bottom member, a series of comb-like teeth extending upwardly from 5 said bottom member and arranged between said key levers, a rear member extending upwardly from said bottom member, and a series of comb-like teeth extending forwardly from said rear member and arranged 10 between said key levers.

6. In a shorthand machine, a series of key levers, each having an upstanding arm near its rear end, a pivot for said key levers, and means for guiding said key levers, said 15 means including a series of comb-like teeth between the key levers at a point adjacent to and in front of said pivot, and a second series of comb-like teeth arranged between said key levers at a point directly above and 20 adjacent to said pivot, the comb-like teeth of each series being integrally connected together and integrally connected to the teeth of the other series, and the teeth of one series being arranged at an angle to the 25 teeth of the other series.

7. In a shorthand machine, a series of pivoted key levers, each of said key levers having an arm which extends forwardly from the pivot and an arm extending upwardly from the pivot, and an angular key 30

lever guide comprising an approximately L-shaped pocket having a bottom wall which lies below the forwardly extending arms, a rear wall at the rear of the upwardly extending arms, comb-like teeth extending 35 forwardly from said rear wall and arranged between said upwardly extending arms, and comb-like teeth extending upwardly from said bottom wall and arranged between said forwardly extending arms.

8. In a shorthand machine, a series of pivoted key levers, each of said key levers having an arm which extends forwardly from the pivot and an arm extending upwardly from the pivot, and an angular key 40 lever guide comprising an approximately L-shaped pocket having a bottom wall which lies below the forwardly extending arms, a rear wall at the rear of the upwardly extending arms, comb-like teeth extending forwardly from said rear wall and arranged between said upwardly extending arms, and comb-like teeth extending upwardly from 45 said bottom wall and arranged between said forwardly extending arms, the bottom and 50 rear walls of said approximately L-shaped pocket and all of said comb-like teeth being integrally connected together.

WARD S. IRELAND.
WALTER E. LIPPERT.
